FURNITURE PANEL OR THE LIKE

Richard M. Chapin, Charlotte, N.C., assignor to Dolly Madison Industries, Huntingburg, Ind.

Filed Apr. 20, 1972, Ser. No. 246,112

Term of patent 7 years

Int. Cl. D6—06

U.S. CL. D6—193

FIG. 1 is a front perspective view of a panel showing my new design;

FIG. 2 is an enlarged vertical sectional view taken along line 2—2 in FIG. 1;

FIG. 3 is an enlarged vertical sectional view taken along line 3—3 in FIG. 1; and

FIG. 4 is a fragmentary horizontal sectional view taken along line 4—4 in FIG. 1.

The back of the panel is shown substantially plain and unornamented.

I claim:

The ornamental design for furniture panel or the like, substantially as shown and described.
